Primary Examiner — Cynthia Ramirez(74) *Attorney, Agent, or Firm* — Cherskov Flaynik & Gurda, LLC(57) **CLAIM**

The ornamental design for a lifting jack, as shown and described.

DESCRIPTION

FIG. 1 is a front, perspective view of the lifting jack showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures are for the purpose of illustrating environment and form no part of the claimed design.
